American Can Company, New York, N. Y., a
corporation of New Jersey

Application August 21, 1941, Serial No. 407,836

3 Claims. (Cl. 221—23)

This invention relates in general to containers which are closed by means of a friction plug and more particularly to a novel combination friction top and dispensing spout construction, which is especially adapted for the ready dispensing of liquid contents.

An object of the invention is the provision of a novel friction top and spout combination, especially adapted for liquid carrying containers, which not only effectively seals and reseals the container while the contents are being shipped or gradually used up but which also permits the simultaneous presence of both the friction plug and the spout in frictional engagement with the friction ring without interference between plug and spout.

Another object of the invention resides in a friction ring construction for such a friction plug and spout combination which provides at the same time a friction seat wall for the sealing plug and a swivel bearing for the dispensing spout and which permits the insertion and removal of the plug while the spout remains in the bearing.

Another object of the invention is the provision of such a combination which permits a rotating movement of the spout into projected pouring position beyond the periphery of the container and into non-pouring position within the confines of the container top.

Still another object of the invention is the provision of such a friction top and spout construction having the enumerated and other advantages which may be produced economically by simple die operations on available equipment.

Numerous other objects and advantages of the invention will be apparent as it is better understood from the following description, which, taken in connection with the accompanying drawing, discloses a preferred embodiment thereof.

Referring to the drawing:

Figure 1 is a perspective view of the upper portion of a cylindrical type of liquid dispensing container illustrating one exemplary embodiment of the invention and showing the friction plug in sealing position and the spout in non-pouring position.

Fig. 2 is a perspective view similar to Fig. 1 showing the friction plug removed and the spout rotated into projected pouring position.

Fig. 3 is a sectional view of the container and spout taken along lines 3—3 of Fig. 2 and showing details of ring and spout construction, and

Fig. 4 is a detail sectional view of the container top construction taken along lines 4—4 of Fig. 1.

Referring in more detail to the preferred em-

bodiment of the invention exemplified in the drawing, Figs. 1 to 4 illustrate the upper portion of a cylindrical sheet metal body 11, closed at the top by means of a sheet metal end member or friction ring 12 in a slip joint 13, which may be effected by mere frictional engagement between the top edge of the body and the end flange or may be made permanent by seaming or soldering. Inwardly of the joint 13, the ring 12 is slightly countersunk and comprises an annular substantially horizontal panel section 14. Thence the metal of the ring is bent downwardly and outwardly, at an acute angle, defining an opening edge bead 15, thence horizontally inwardly to provide a recessed annular shoulder 16, and thence vertically downwardly terminating in a raw bottom edge to provide a smooth annular depending friction seat wall 17. The parts 15, 16, and 17 define a friction ring opening 18, which preferably is located eccentrically of the friction ring 12 for a purpose which will become clear as the description proceeds.

The bead 15, the shoulder 16 and the oblique wall connecting these parts provide a swivel bearing for a pouring spout A and the depending wall 17 provides a friction seat for a friction plug closure element B.

The dispensing spout A preferably comprises a tapered pouring lip 19, which merges rearwardly into two segmental or annular side wings 21. Each wing 21 consists of an outer flange 22 and an inner flange 23 connected by a bend or bead 24, which disposes the two flanges at an acute angle to each other. By reference to Figs. 3 and 4 it will be noted that the outer flange 22 overlies and engages a portion of the panel 14 and terminates in a rounded bead or curl 25 which is continued on the tapered sides of the pouring lip 19. The bead 24 and the inner flange 23 respectively overlie and hug the bead 15 and the downwardly and outwardly bent wall of the friction ring, the flange 23 terminating in the raw edge adjacent the shoulder 16 of the ring, these parts providing a swivel bearing for the spout A.

The friction plug B preferably comprises a dish shaped cylindrical one piece shell having a deep vertical wall 26, merging into a closed bottom wall 27 and at its top the plug wall 26 is bent outwardly, downwardly and inwardly to provide a stop shoulder 28 which overlies and engages the flange 22 of the spout to limit the inward movement of the plug.

When the spout A and plug B are fully assembled within the friction ring 12 they assume the position shown in detail in Fig. 4. With ref-

erence to Fig. 4, it will be seen that the lower portion of the wall 26 of the plug frictionally engages the depending friction seat wall 17 of the ring 12, thereby effectively sealing the container. The upper portion of the wall 26 on the other hand fully clears the flange 23 and bead 24 of the spout and may be slightly spaced away from the same, so that the plug B at no time interferes with the operation of the spout A.

When the described container is used for shipping and dispensing liquids (and it is adaptable for a great variety of liquids and may even be used for free flowing solid products) the spout and plug are assembled within the friction top of the container in the position shown in Fig. 1, with the spout confined within the countersunk end in non-pouring position. When the filled container reaches the ultimate consumer and the contents are to be dispensed, the spout A is projected into the dispensing position shown in Fig. 2. The projection is preferably done after the plug B has first been removed, although the described construction will permit the rotation of the spout even before removal of the plug. The container is then tilted into pouring position and the contents may be dispensed completely or intermittently as desired, the plug B reclosing the container when not in use.

While the drawing shows the invention embodied in a cylindrical container made of sheet metal, the invention is applicable to containers of a variety of different shapes and materials. For example the body might be a glass jar closed by a sheet metal screw cap having the described friction top construction eccentrically located in the cap, or the shape of the body might be rectangular with the dispensing opening of the end positioned to one side of the container. Also the joint 13 disclosed in Fig. 3 might be changed to the well known double seam. All such modifications are considered to be within the scope and spirit of the present invention.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. A combined friction plug and spout contain-

er, comprising in combination, a container body having an end member thereon, said end member having an opening located eccentrically therein, the material of said end closure defining said opening being inclined downwardly and thence inwardly to form a shoulder and recess bearing for the reception of a spout and thence extending downwardly to constitute a friction seat wall disposed below said bearing for the reception of a friction plug, a spout rotatably seated in said bearing and a friction plug overlying said spout and having frictional sealing engagement with said friction seat wall, the seating wall of said spout being spaced radially outwardly relative to the seating wall of said plug to permit rotation thereof irrespective of the presence of the plug.

2. A container having a combined friction plug and spout construction, comprising in combination, a container body and end closure for said body, said end closure comprising a substantially horizontal panel having an opening located eccentrically therein, the material of said panel defining said opening being inclined downwardly and outwardly, thence substantially horizontally inwardly to provide a shoulder and recess bearing and thence downwardly to provide a friction seat wall, a spout rotatably seated in said bearing and a friction plug overlying said spout and bearing and sealingly engaging said friction seat wall and spaced from said spout and bearing to permit said spout to be moved into pouring position with the spout lip projecting beyond the edge of the end closure and into non-pouring position within the confines of said end closure.

3. A pouring spout container comprising a container body having an end member secured thereto, said end member having a depending annular wall defining an opening therein, said wall including radially spaced inner and outer portions constituting separate friction seats, a spout member having a depending wall frictionally engaging the outer of said end member seats for revolvably mounting the spout on said end member, and a friction plug closure element disposed radially inwardly of said spout member and having a depending wall frictionally engaging the inner of said end member seats, whereby to provide rotary movement of said spout member relative to said end member independently of the frictional engagement of said plug closure element with said end member.

ROBERT NYDEN.
